(57) **CLAIM**

The ornamental design for a case for electronic communications device, as shown and described.

DESCRIPTION

FIG. 1 is a front perspective view of a case for electronic communications device showing my new design in an environment of use;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing the front outer frame component of the case in isolation;

FIG. 10 is a rear perspective view showing the front outer frame component of the case in isolation;

FIG. 11 is a front perspective view showing the rear outer frame component of the case in isolation;

FIG. 12 is a rear perspective view showing the rear outer frame component of the case in isolation;

FIG. 13 is an exploded front perspective view showing the front outer frame component and rear outer frame component separated from each other and separated from the environmental subject matter for clarity of disclosure; and, FIG. 14 is an exploded rear perspective view showing the front outer frame component and rear outer frame component separated from each other and separated from the environmental subject matter for clarity of disclosure.

For clarity of disclosure, the components of the case for electronic communications device are shown in isolation in FIGS. 9–12 and separated in FIGS. 13–14. Although the case for electronic communications device, in which the claimed design is embodied, has a front outer frame component and a rear outer frame component, the claim is directed to the overall ornamental appearance of the case in its entirety and does not extend to the ornamental appearance of each of the individual components.

The broken lines throughout the drawing figures depict environmental subject matter and portions of the case for electronic communications device that form no part of the claimed design.
